Attorney

UNITED STATES PATENT OFFICE.

EDWARD A. FALL, OF RUTHERFORD, NEW JERSEY.

TANK CAR.

Application filed June 27, 1923. Serial No. 648,171.

The present invention relates to improvements in tank cars, and particularly to means for heating the outlets of such cars in which liquid or semi-liquid materials are transported.

The outlets of the tanks of tank cars employed for transporting such materials, as asphaltum, and similar bitumen products, frequently become clogged, especially in cold weather, and to enable the contents of the tank to be drawn therefrom, it is necessary to apply heat to the outlets.

The particular object of the present invention is to provide a means whereby the outlet of such a tank car will be heated, and the heating medium employed also used to heat the body of the tank adjacent the outlet, so as to facilitate the flow of material to such outlet.

20 In the accompanying drawings:—

Fig. 1 is a view in partial elevation and part section of a tank car outlet having an embodiment of the present invention applied thereto.

25 Fig. 2 is a view substantially on the line 2—2 of Fig. 1.

Fig. 3 is a view, similar to Fig. 1, illustrating a slightly different embodiment of the invention.

30 Fig. 4 is a detail.

Fig. 5 is a horizontal section of another embodiment.

Fig. 6 is a section substantially on the line 6—6 of Fig. 5.

35 Fig. 7 is a section on a line substantially at right angles to the plane of section of Fig. 6 of the parts shown in Figures 5 and 6.

In the drawings, wherein like reference characters designate corresponding parts in the several views, only a small portion of the tank and supporting parts of the car frame are illustrated, and such illustration is more or less conventional.

40 Referring to the drawings, 1 designates a pair of beams or girders of the car frame, shown as being formed of angle iron, and 2 indicates a portion of the bottom of the tank supported from the car frame and provided with an aperture 3, about which is suitably secured a depending outlet 4. The lower

end of the outlet 4 is threaded, as at 5, for the attachment of a suitable nozzle, not shown.

A suitable casing is supported to surround the outlet 4, and is provided, adjacent its lower end, with an inlet 6 adapted to be connected to a pipe or conduit, through which any suitable heating medium, such as steam, may be supplied to the interior of the casing and caused to heat the wall of the depending outlet 4.

45 Preferably, as shown, the casing is in the form of a sleeve having an insulating layer 7 in its side wall, and expanded, as at 8, adjacent its upper end. A gasket 9 is fitted in a groove in the upper end of the sleeve-like casing, and the latter is so supported from the car frame that the ring or gasket 9 is forced into close contact with the base of the outlet 4, or the surrounding portion of the tank bottom, to make a fluid-tight joint therewith.

The sleeve or casing is closed at its lower end by a flexible diaphragm 10 apertured to receive the outlet 4, said flexible bottom being, as shown, deflected downward and contacting with the side wall of the outlet, as at 11. This provides a construction by which the heating medium will be prevented from escaping downward about the outlet, but a plurality of apertures 12 are provided in the upper, enlarged, portion of the casing, through which the heating medium may escape therefrom.

50 In the embodiment of the invention illustrated in Figs. 1 and 2, the casing is provided with diametrically opposite, laterally projecting, arms 13, which extend over the upper flanges of the car frame members 1, and in each of said arms is formed an internally threaded passage through which extends a screw 14. Said screws extend downward from the arms 13 and bear upon the upper flanges of the supporting beams 1. It will be seen that by turning the screws 14, the arms 13 and the casing will be moved upward and the gasket 9 compressed against the tank bottom or the base of the outlet 4, and the casing securely clamped in such elevated position.

55 Means are provided whereby the steam,

or other heating medium, escaping from the openings 12, is guided along the bottom of the tank in the direction of the length of the beams 1, instead of escaping directly into the air, so that the full heating effect of such medium may be utilized and applied to the contents of the tank.

In the embodiment of the invention illustrated in Figs. 1 and 2, a channel, extending longitudinally of the beams 1, and between such beams and the bottom of the tank, is formed by filler blocks or strips 20. Said strips are of such height as to fit closely between the top flanges of the beams 1 and the bottom of the tank, and, if desired, suitable securing means may be provided for retaining them in position. Suitable notches or recesses are formed in the strips 20 to receive the ends of the arms 13, and the screws 14, by which such arms are connected to the car frame beams. If desired, the recesses may be shaped to conform to the contour of the arms 13, in which case the strips 20 are divided, as at 21, as shown in full lines in the drawing. However, it may be preferred to merely form the recesses or notches of rectangular form, as shown in dotted lines in Fig. 2, and in this event, the filler strips may be continuous from end to end. By this arrangement, it will be seen that the heating medium, passing through the openings 12, will be guided in a direction longitudinal of the beams 1 along the bottom of the tank in both directions from the outlet 4, and the heat thereof utilized to maintain the contents of the tank in a fluid condition, so that they will readily flow from the outlet which has also been sufficiently heated to prevent congealing of the tank contents therein.

In the embodiment of the invention illustrated in Fig. 3, the invention is illustrated as applied to a different type of tank car from that shown in Figs. 1 and 2. In this embodiment of the invention, the casing surrounding the tank outlet is supported by posts 22 from arms 23 that are secured by bolts 24 to the lower flanges of the car frame beams or girders 1, and extend inwardly therefrom. The uprights are shown as provided with enlarged heads 25 from which extend upwardly studs 26 that engage suitable sockets or apertures in the enlarged upper end of the casing. Reinforcing blocks 29 are preferably arranged between the heads 25 of the supporting posts and the annular flanges surrounding the upper end of the casing.

In this embodiment of the invention, the tank 2 is provided with depending parallel flanges 27 that extend downward between the car frame beams 1, and the portions of these flanges between the tops of the beams 1 and the bottom of the tank form a channel receiving the heating medium that es-

capes from the openings 12. As shown, said flanges are portions of angle iron plates, the other members 28 of which are suitably secured to the tank bottom.

Instead of forming the channel by which the heating medium, escaping from the casing surrounding the tank outlet, is conducted along the bottom of the tank by members independent of the casing and co-operating with the tank and the supporting beams 1 of the car as described, suitable trough-like members 30 may be secured directly to the upper portion of the casing, as by rivets 31, the upturned side flanges of such trough-like members extending into contact with the tank bottom, and forming channels into which the apertures 12 in the casing open.

It will be seen that in all of the embodiments of the invention, means are provided whereby the steam or other heating medium, applied to the casing surrounding the tank outlet, is conducted along the bottom of the tank after escaping from said casing.

There can, of course, be modification of some of the parts illustrated without departing from the invention, and, therefore, unless the same are particularly referred to in the appended claims, it is not desired to limit the invention to the exact details shown.

Having thus described the invention, what is claimed is:

1. The combination with a tank car having an outlet for the contents of the tank depending from the tank body, of a casing supported independently of and surrounding the tank outlet and provided with an inlet for a heating medium, and having a discharge aperture in its vertical wall adjacent its upper end whereby the heating medium passing through said discharge aperture will contact with the bottom of the tank body outside of said casing.

2. The combination with a tank car having an outlet for the contents of the tank depending from the tank body, of a casing surrounding the tank outlet and provided with an inlet for a heating medium, and having a plurality of discharge apertures in its vertical wall, and means providing a plurality of channels for the heating medium along the bottom of the body of the tank car, each communicating with one of said discharge apertures, for the purpose described.

3. The combination with a tank car having an outlet for the contents of the tank depending from the tank body, of a casing surrounding the tank outlet and provided with an inlet for a heating medium and having a plurality of discharge apertures in its vertical wall, and means providing two channels for the heating medium extending in opposite directions from said

casing along the bottom of the body of the tank car, and each communicating with one of the discharge apertures in the casing.

4. The combination with a tank car having an outlet for the contents of the tank depending from the tank body, of a casing surrounding said depending tank outlet and having an inlet for a heating medium and a discharge aperture, and means for causing the heating medium to travel along the tank bottom after leaving said casing.

5. The combination with a tank car having an outlet for the contents of the tank depending from the tank body, of a casing surrounding said depending tank outlet and having an inlet for a heating medium and a discharge aperture, and means forming a channel extending along the bottom of the tank with which the discharge aperture of said casing communicates.

6. The combination with a tank car having an outlet for the contents of the tank depending from the tank body, a casing surrounding the tank outlet and having an opening in its bottom through which the outlet extends, said casing being provided with an inlet for a heating medium and a lateral discharge aperture adjacent its upper end, and means for conducting the heating medium passing through said discharge aperture along the adjacent bottom portion of the tank.

7. The combination with a tank car having an outlet for the contents of the tank depending from the tank body, a sleeve supported about the tank outlet with its upper end forming a fluid tight joint with the tank bottom, and a flexible bottom closing the space between the lower end of said sleeve and the tank outlet, said sleeve being provided with an inlet for a heating medium.

8. The combination with a tank car having an outlet for the contents of the tank depending from the tank body, a sleeve supported about the tank outlet with its upper end forming a fluid tight joint with the tank bottom, means closing the space between the lower end of said sleeve and the adjacent wall of the tank outlet, said sleeve being provided with an inlet for a heating medium and a discharge aperture for such medium, and means for conducting the heating medium from said discharge aperture along the bottom of the tank.

55 9. The combination with a tank car having an outlet for the contents of the tank depending from the tank body between parallel beams of the car frame, of a casing surrounding the tank outlet between said beams and supported from the latter with its upper end in close contact with the tank, said casing being provided with an inlet for a heating medium and with a discharge aperture for such medium, and means forming a channel extending along the bottom

of the tank and with which the discharge aperture of the casing communicates.

10. The combination with a tank car including a frame provided with parallel beams and a tank on the frame having an outlet for the contents thereof extending downward between said beams, of a sleeve supported by said beams about the tank outlet with its upper end in close contact with the tank body, and means closing the space between the lower end of said sleeve and the tank outlet, said sleeve being provided with an inlet for a heating medium and a discharge aperture permitting the heating medium to pass therefrom into contact with the body of the tank.

11. The combination with a tank car including a frame provided with parallel beams and a tank on the frame having an outlet for the contents thereof extending downward between said beams, of a casing surrounding the tank outlet and having an inlet for a heating medium and a discharge aperture for such medium, and means interposed between the tank and beams and forming a channel with which said discharge aperture communicates.

12. The combination with a tank car including a frame provided with parallel beams and a tank on the frame having an outlet for the contents thereof extending downward between said beams, of a casing surrounding the tank outlet and having an inlet for a heating medium and a discharge aperture for such medium, and means interposed between the tank and beams and forming a channel extending along the bottom of the tank in the direction of the length of the beams with which said discharge aperture communicates.

13. The combination with a tank car including a frame provided with parallel beams and a tank on the frame having an outlet for the contents thereof extending downward between said beams, of a sleeve supported from said beams and surrounding the depending tank outlet, adjustable means for maintaining a fluid tight connection between the upper end of said sleeve and the tank, means closing the space between the lower end of the sleeve and the tank outlet, said sleeve having an inlet for a heating medium and an aperture through which said medium may pass from the space about the tank outlet.

14. The combination with a tank car including a frame provided with parallel beams and a tank on the frame having an outlet for the contents thereof extending downward between said beams, the bottom of the tank being vertically spaced from the beams adjacent said outlet, a casing surrounding the tank outlet and having an inlet for a heating medium and a discharge aperture through which said medium can pass

- from the casing, and means between the beams and tank forming a channel with which the said discharge aperture of the casing communicates.
- 5 15. The combination with a tank car including a frame provided with parallel beams and a tank on the frame having an outlet for the contents thereof extending downward between said beams, and a casing 10 surrounding the tank outlet and having diametrically opposite projecting arms extending over said beams and supporting the casing therefrom, said casing having an inlet for a heating medium.
- 15 16. The combination with a tank car having an outlet for the contents of the tank depending from the tank body, of a casing surrounding said tank outlet and having an inlet for a heating medium and a dis- charge aperture for such medium, and a 20 member of channel form in cross section secured to and projecting laterally from said casing in alignment with the discharge aperture therein.
17. The combination with a tank car having an outlet for the contents of the tank depending from the tank body, of a casing surrounding said tank outlet and having an inlet for a heating medium and a plurality 25 of discharge apertures for such medium, and two diametrically opposite members of channel form in cross section, each communicating with a discharge aperture in the casing.
- In testimony whereof I have hereunto set 30 my hand.

EDWARD A. FALL.
